GEORGE S. SMITH, OF BOZRAHVILLE, CONNECTICUT.

Letters Patent No. 92,218, dated July 6, 1869.

IMPROVEMENT IN YARN-EVENER.

The Schedule referred to in these Letters Patent and making part of the same.

To all whom it may concern:

Be it known that I, GEORGE S. SMITH, of Bozrahville, in the State of Connecticut, have invented a new and useful Improvement in Yarn-Eveners; and I do hereby declare that the following is a full, clear, and exact description of the same, reference being had to the accompanying drawings, and letters of reference marked thereon, making a part of this specification, in which—

Figure 1 is an end elevation, and

Figure 2 is a side elevation, the two vertical shafts being removed.

To enable those skilled in the art to make and use my invention, I now proceed to describe its construction and operation.

Similar letters in the drawings refer to like parts.

This invention is designed as an improvement in mechanism for evening yarn in spinning-machinery.

It consists in passing the thread, while on its way from the bobbin to the spool, between a pair of needle-points, for the purpose of loosening imperfections, such as bunches, knots, and the like, in order that they may be more effectually removed by the trimmers provided for the purpose.

In the drawings—

A represents a vertical wooden block, which is intended to be secured to a horizontal rail, not shown, said rail being attached to the frame of the spooling-machinery.

The block A is provided with a metallic plate, B, projecting at right angles from its lower side, and supporting two small vertical shafts, whereof the outer one, C, is rigidly attached to the plate, and being provided with a circumferential groove, c, for the thread to run in, as it encircles the shaft on its way from the bobbins, forms a friction-stud.

The shaft D is attached to the plate by means of a screw, d, in such a manner that the shaft may be made

to project to a greater or less distance, at pleasure, from the plate B. This shaft being provided with a transverse groove in its outer end for the thread to traverse, forms a tension-stud to tighten and harden the thread.

From the stud, the thread passes between two needles, E E, whose points converge, and being each set in an adjustable plate, F, may be placed as near to or far from each other as may suit the size of the yarn.

The function of the needles E is to loosen bunches in the thread formed by seeds spun into its texture, or by two ends twisting together, or in a variety of other ways, well known to manufacturers, which bunches are removed by the trimmers F' F', through which the thread next passes, said trimmers consisting of two steel plates, sunk into the side of the block A, flush with its surface, and fastened to said block by means of screws x x passing through slots in the plates.

The contiguous edges of the trimmers having sharp corners, may, by this means, be adjusted according to the size of the thread, and may be depended on to finish the work of evening begun by the needles E E. From the trimmers F' the thread passes on to the spool in a fit condition to be wound.

Having thus described my invention,

What I claim as new, and desire to secure by Letters Patent, is—

The adjustable needles E E, in combination with the adjustable trimmers F' F', in a spooling-mechanism, arranged and operating substantially as and for the purpose set forth.

GEO. S. SMITH.
